ABSTRACT

A radial out-flowing rotary ram-in compressor for use in gas turbine engines and the like, having a plurality of vanes attached to discs, with the opposing parts of each two adjacent vanes defining a feeding channel in-between. In operation, working gases are rammed through the feeding channels in a generally radially outward direction, followed by positive displacement of the rammed-in gases to a receiver wherein pressurized gases collect. The pressurized gases are actively swept from the receiver by either a successive rotary ram-in compressor or a successive rotary ram compressor.

CROSS-REFERENCE TO RELATED APPLICATION(S)

This non-provisional utility patent application claims the benefit of one prior filed non-provisional application; the present application is a continuation-in-part of U.S. patent application Ser. No. 10/669,514, filed Sep. 23, 2003, now U.S. Pat. No. 6,877,951, which is incorporated herein by reference in its entirety.

FIELD OF THE INVENTION

The present invention relates to a positive displacement compressor and, more particularly, to a rotary positive displacement compressor convenient for use in gas turbine engines and the like.

BACKGROUND OF THE INVENTION

Rotary compressors are well known devices, used in several fields to develop a pressure gradient between two points across a stream of working gases. Two main types of rotary compressors are in use, dynamic compressors, i.e., centrifugal flowing, axial flowing, and the combined types, and positive displacement compressors. In dynamic compressors the working gases are accelerated followed by its deceleration within diverging passages, wherein part of its kinetic energy is converted into static pressure rise. In positive displacement compressors the pressure is increased by reducing the specific volume of the gases during their passage through the compressor.

Dynamic Compressors are widely in use in gas turbine and steam engines as they are able to raise the pressure of a relatively large volume of working gases while operating at relatively high rotational speeds. On the contrary, conventional types of positive displacement rotary compressors are not convenient for use in gas turbine engines, and the like, as the friction between the rubbing parts within them limits their practically useful range of operating rotational speeds.

Prior art, which is not relied upon, includes U.S. Pat. No. 4,227,868 by Nishikawa et al., U.S. Pat. No. 4,278,399 by Erickson, U.S. Pat. No. 4,358,244 by Nishikawa et al., U.S. Pat. No. 6,739,835 by Kim, Japan Pat. No. JP354013002A, Japan Pat. No. JP35508794A, and German Pat. No. DE3243169A1. Each of them showing a compressor impeller having a first disk and a second disk and a plurality of vanes arranged there between.

SUMMARY OF THE INVENTION

The present invention provides a rotary positive displacement compressor having no rubbing parts within, which allows its use in the applications wherein relatively high operating rotational speeds are needed.

Also, the present invention provides a radial out-flowing rotary positive displacement compressor, wherein the working gases are displaced to a compressor's receiver in a generally radially outward direction, for use in gas turbine engines, and the like, wherein other design parameters favor the use of a radial out-flowing compressor arrangement.

Accordingly, the present invention provides a radial out-flowing rotary ram-in compressor having a plurality of feeding channels, moving at high speed, through which

working gases are rammed in a generally radially outward direction, followed by positive displacement of the rammed in gases to a receiver.

In a preferred embodiment, the radial out-flowing rotary ram-in compressor comprises a stationary casing having at least one inlet passage, for admission of working gases, and a receiver; a drive shaft supported for rotation in a given direction inside the casing by an arrangement of bearings; and a rotor assembly comprising a first disk secured for rotation with the drive shaft and lying in a first plane transverse to the rotational axis of the drive shaft; a second disk lying in a second plane transverse to the rotational axis of the drive shaft, with the inner surfaces of the two disks defining an annular space in-between; and a plurality of 10 vanes arranged circumferentially within said annular space, each vane attached to both disks defining the annular space, each vane has a leading edge, a trailing edge, a concave surface and a convex surface, with the average angles of 15 inclination of the successive portions of the vane with respect to a plane comprising the midpoint of the vane and perpendicular to a radial plane including the rotational axis of the rotor and the midpoint of the vane decreases preferably 20 gradually from its leading edge towards its trailing edge, within a range from about +20 to about -10 degrees, the opposing parts of the surfaces of each two adjacent vanes along with the opposing parts of the surfaces of each two disks' surfaces 25 confined between the opposing parts of the surfaces of each two adjacent vanes defining a feeding channel between them, each feeding channel has an inlet communicating with the space relatively radially inward of the vanes, and an outlet communicating with the space relatively radially outward of the vanes, with the space relatively radially inward of the vanes being freely communicating with the compressor's inlet passage(s), and with the space relatively 30 radially outward of the vanes being freely communicating with the compressor's receiver, with means for active sweeping of the pressurized gases from the compressor's receiver being provided.

Unlike the rotary ram compressor disclosed in the inventor's earlier International Patent Application Number: PCT/US00/17044, entitled "Rotary ram fluid pressurizing machine", no deceleration of the rammed-in gases occurs within the feeding channels of the radial out-flowing rotary ram-in compressor of the present invention.

In a preferred embodiment of the radial out-flowing rotary ram-in compressor of the present invention, each two opposing surfaces, of those defining each of the feeding channels between them, are parallel to one another, with the cross-sectional area of the inlet of each of the feeding channels 45 being equal to the cross sectional area of its outlet.

In another preferred embodiment, in order to increase the volumetric rate with which the working gases are fed to the radial out-flowing rotary ram-in compressor of the present invention, each of the feeding channels is slightly converging from its inlet towards its outlet. The convergence of the feeding channel is provided by designing the boundaries confining the channel between them so that the axial width of the channel and/or the width between the opposing parts 50 of the surfaces of the two adjacent vanes confining the channel between them decrease preferably gradually from the inlet of the channel towards its outlet, and hence, the cross-sectional area of the channel decreases preferably gradually from its inlet towards its outlet.

The gradual decrease in the axial width of the feeding channel is provided by designing the part(s) of the surface(s) of one (or both) of the disks related to the channel and confined between the opposing parts of the surfaces of the

two adjacent vanes so that it is sloping preferably gradually from the inlet of the channel towards its outlet. The gradual decrease in the width between the opposing parts of the surfaces of the two adjacent vanes is provided by designing the vanes with suitable angles of inclination at their different parts, according to the desired rate of convergence of the channel.

In operation, working gases are rammed through the feeding channels of the compressor, which direct it to the space relatively radially outward of the vanes. The rammed in gases are first compressed by both the pressurized gases collecting within the compressor's receiver and by the reaction force developed on the free parts of the convex surfaces of the vanes next to the outlets of the feeding channels, then, the pressurized freshly introduced gases are displaced in a generally radially outward direction to the compressor's receiver, by the relatively outer free parts of the convex surfaces of the vanes. As used herein, the free part of the convex surface of a vane refers to the part of the convex surface of the vane that is not opposed by any part of the surfaces of its adjacent vanes.

In a preferred embodiment, a successive rotary ram compressor is used for active sweeping of gases from the radial out-flowing rotary ram-in compressor's receiver, as the static pressure rise developed within the diverging channels of the rotary ram compressor prevents excess flow of the pressurized gases from the receiver through its channels, with the density and the pressure level of the gases within the receiver being dependant on the ratio between the volumetric rate with which working gases are fed to the receiver by the radial out-flowing rotary ram-in compressor (which depends on the number of its feeding channels, and their dimensions and velocity) and the volumetric rate with which gases are swept from the receiver by the rotary ram compressor (which depends on the number of its channels, the dimensions of its channels' inlets, and their velocity).

In another preferred embodiment, a successive rotary ram-in compressor (either a radial in-flowing or a radial out-flowing one) is used for active sweeping of gases from the compressor's receiver, as the static pressure rise developed within the receiver of the second rotary ram-in compressor prevents excess flow of gases from the receiver of the first radial out-flowing rotary ram-in compressor through the feeding channels of the second rotary ram-in compressor, with the density and the pressure level of the gases within the receiver of the first radial out-flowing rotary ram-in compressor being dependant on the ratio between the volumetric rate with which gases are fed to the receiver and the volumetric rate with which gases are swept from it.

If the volumetric rate with which gases are fed to the compressor's receiver equals the volumetric rate with which it is being swept from it, no pressure rise occurs within the receiver, with the pressure inside it being equivalent to that of the gases at the compressor's inlet. If the volumetric rate with which gases are fed to the receiver is greater than its sweeping volumetric rate, the density of gases within the receiver, and hence its pressure, will gradually increase till an equilibrium point is reached, at which the mass flow rates of gas feeding and gas sweeping to and from the receiver are equal to one another.

The maximum allowable pressure level of the gases within the compressor's receiver, at a given operating rotational speed, depends on the velocity with which the feeding channels moves, which should exceed the velocity with which the pressurized gases tends to flow back from the compressor's receiver to the feeding channels, due to the developed pressure gradient between them.

The velocity of the feeding channels of the radial out-flowing rotary ram-in compressor is kept below the speed of sound to avoid the formation of shock waves, which if formed will interfere with the free ingestion of working gases by the feeding channels.

BRIEF DESCRIPTION OF THE DRAWINGS

The description of the objects, features and advantages of the present invention, will be more fully appreciated by reference to the following detailed description of the exemplary embodiments in accordance with the accompanying drawings, wherein:

FIG. 1 is a sectional view in a schematic representation of an exemplary embodiment of a radial out-flowing rotary ram-in compressor, in accordance with the present invention.

FIG. 2 is a cross sectional view, taken at the plane of line 2—2 in FIG. 1.

FIG. 3 is a cross sectional view, taken at the plane of line 3—3 in FIG. 1.

FIG. 4 is a sectional view in a schematic representation of another exemplary embodiment of a radial out-flowing rotary ram-in compressor, in accordance with the present invention.

FIGS. 5—10 are schematic representations of alternative ways in which the feeding channels confined between the opposing parts of the surfaces of the adjacent vanes of a radial out-flowing rotary ram-in compressor in accordance with the present invention, may be designed.

DETAILED DESCRIPTION OF THE PREFERRED EMBODIMENTS

Prior filed U.S. patent application Ser. No. 10/669,514, entitled "Rotary ram-in compressor" provides a rotary ram-in compressor for use in gas turbine engines, and the like, having a plurality of vanes attached to discs, with the opposing parts of each two adjacent vanes defining a feeding channel in-between. In operation, working gases are rammed through the feeding channels, followed by positive displacement of the rammed-in gases to a receiver wherein pressurized gases collect. The pressurized gases are actively swept from the receiver by either a successive rotary ram-in compressor or a successive rotary ram compressor (disclosed in the inventor's earlier International Patent Application Number: PCT/US00/17044, entitled "Rotary ram fluid pressurizing machine"). In the exemplary embodiments provided in the before mentioned prior patent application, working gases are displaced in a generally radially inward direction, which makes it inconvenient for use in the applications wherein other design parameters favor the use of a radial out-flowing compressor arrangement.

The present application clearly defines a radial out-flowing rotary ram-in compressor, wherein the rammed in working gases are displaced to the compressor's receiver in a generally radially outward direction, for use in the applications wherein other design parameters favor the use of a radial out-flowing compressor arrangement.

FIG. 1 is a sectional view in a schematic representation of an exemplary embodiment of a radial out-flowing rotary ram-in compressor, in accordance with the present invention.

The main components of the radial out-flowing rotary ram-in compressor in this embodiment are a stationary casing (21) having an inlet passage (22) for admission of working gases (23), and a receiver (24) wherein pressurized

gases (25) collect; a drive shaft (26) supported for rotation in a given direction inside the casing by an arrangement of bearings (27), and extending to a drive receiving end located outside the casing; and a rotor assembly housed inside the casing and secured for rotation with the drive shaft (26).

The rotor assembly comprises a first disk (29) secured for rotation with the drive shaft (26) and lying in a first plane transverse to the rotational axis of the drive shaft; a second disk (30) having a large open center and a widened rim, and lying in a second plane transverse to the rotational axis of the drive shaft, with the inner surfaces of the two disks defining an annular space in-between; and a plurality of vanes (31) arranged circumferentially within said annular space, each vane attached to both disks defining the annular space. As shown in FIG. 2 which is a cross sectional view, taken at the plane of line 2—2 in FIG. 1, each vane (31) has a leading edge (32), a trailing edge (33), a concave surface (34) and a convex surface (35), with the average angles of inclination of the successive portions of the vane with respect to a plane comprising the midpoint of the vane and perpendicular to a radial plane including the rotational axis of the rotor and the midpoint of the vane decreases preferably gradually from its leading edge towards its trailing edge, within a range from about +20 to about -5 degrees, the opposing parts of the surfaces of each two adjacent vanes along with the opposing parts of the two disks' surfaces confined between the opposing parts of the surfaces of each two adjacent vanes defining a feeding channel (36) between them, each feeding channel (36) having an inlet (37) communicating with the space relatively radially inward of the vanes (38), and an outlet (39) communicating with the space relatively radially outward of the vanes (40), with the space relatively radially inward of the vanes (38) being freely communicating with the compressor's inlet passage (22), and with the space relatively radially outward of the vanes (40) being freely communicating with the compressor's receiver (24). The embodiment also includes a rotary ram compressor (28) for active sweeping of the pressurized gases (25) from the rotary ram-in compressor's receiver (24).

In operation, working gases (23) are rammed through the feeding channels (36) of the compressor, which direct it to the space relatively radially outward of the vanes (40). The rammed in gases are first compressed by both the pressurized gases (25) collecting within the compressor's receiver (24) and the reaction force developed on the free parts of the convex surfaces of the vanes (35) next to the outlets of the feeding channels (39), then, the pressurized freshly introduced gases are displaced in a generally radial outward direction to the receiver (24), by the relatively outer free parts of the convex surfaces of the vanes (35). The pressurized gases (25) are actively swept from the receiver (24) by the rotary ram compressor (28), which is driven by another driving shaft (41).

As also shown in FIG. 3 which is a cross sectional view, taken at the plane of line 3—3 in FIG. 1, the radial out-flowing rotary ram-in compressor's receiver (24) forms the inlet passage (42) of the rotary ram compressor (28) used for active sweeping of the pressurized gases (25). The static pressure rise developed within the diverging channels (43) of the rotary ram compressor (28) prevents excess flow of gases from the receiver (24) through them, with the density and the pressure level of the gases within the receiver (24) being dependant on the ratio between the volumetric rate with which gases are fed to the receiver (24) by the radial out-flowing rotary ram-in compressor and the volumetric rate with which gases are swept from the receiver (24) by the rotary ram compressor (28). The maximum allowable pres-

sure level within the receiver (24), at a given operating rotational speed, will depend on the velocity with which the feeding channels (36) of the rotary ram-in compressor moves, which should exceed the velocity with which the pressurized gases (25) tends to flow back of from the receiver (24) to the feeding channels (36), due to the developed pressure gradient between them.

FIG. 4 is a sectional view in a schematic representation of another exemplary embodiment of a radial out-flowing rotary ram-in compressor, in accordance with the present invention.

The main components of the radial out-flowing rotary ram-in compressor in this embodiment are a stationary casing (51) having an inlet passage (52) for admission of working gases (53), and a receiver (54) wherein pressurized gases (55) collect; a drive shaft (56) supported for rotation in a given direction inside the casing by an arrangement of bearings (57), and extending to a drive receiving end located outside the casing; and a rotor assembly (58) housed inside the casing and secured for rotation with the drive shaft (56). The embodiment also includes a successive radial in-flowing rotary ram-in compressor (59) for active sweeping of the pressurized gases (55) provided by the first radial out-flowing rotary ram-in compressor (60), from the compressor's receiver (54). The design of the radial out-flowing rotary ram-in compressor (60) in this embodiment is quite similar to that of the radial out-flowing rotary ram-in compressor of the embodiment of FIGS. 1, 2. The design of the radial in-flowing rotary ram-in compressor (59) in this embodiment is quite similar to that of the rotary ram-in compressors disclosed in the inventor's earlier U.S. patent application Ser. No. 10/669,514, referred to herein before.

In operation, the pressurized gases (55) provided by the first radial out-flowing rotary ram-in compressor (60) collect within its receiver (54), from which it is actively swept by the feeding channels of the successive radial in-flowing rotary ram-in compressor (59). The pressurized gases (61) provided by the second radial in-flowing rotary ram-in compressor (59) collect within its receiver (62), from which it is actively swept by either a successive rotary ram-in compressor or a successive rotary ram compressor (not included in the drawing for simplicity).

The density and the pressure level of the gases (55) within the receiver (54) of the first radial out-flowing rotary ram-in compressor depends on the ratio between the volumetric rate with which gases are fed to receiver (54) by the first radial out-flowing rotary ram-in compressor (60) and the volumetric rate with which gases are swept from the receiver (54) by the second radial in-flowing rotary ram-in compressor (59). As the first and second rotary ram-in compressors (60, 59) are driven by the same shaft (56), i.e. will have the same operating rotational speed, so, the ratio between their volumetric delivery and sweeping rates, and hence the pressure level of gases (55) within the receiver (54), will depend on the ratio between the total cross sectional area of the inlets of the feeding channels of the first radial out-flowing rotary ram-in compressor (60) and the total cross sectional area of the inlets of the feeding channels of the second radial in-flowing rotary ram-in compressor (59).

FIGS. 5—10 are schematic representations of alternatives in which the feeding channels confined between the opposing parts of the surfaces of the adjacent vanes of a radial out-flowing rotary ram-in compressor in accordance with the present invention, may be designed.

As discussed herein before, the boundaries of each of the feeding channels are formed of the opposing parts of the surfaces of the two adjacent vanes confining the channel

between them (right front and left rear surfaces of the drawings), and of the opposing parts of the disks' surfaces related to the channel and confined between the opposing parts of the surfaces of the two adjacent vanes.

In FIG. 5 each two opposing surfaces (71,72 & 73,74), of those defining the feeding channel between them, are parallel to one another, with the cross-sectional area of the inlet of the channel being equal to the cross sectional area of its outlet.

In FIG. 6 the feeding channel is slightly converging from its inlet towards its outlet. The convergence of the feeding channel is provided by designing the boundaries confining the channel between them so that the axial width of the channel decreases gradually from the inlet of the channel towards its outlet, with the gradual decrease in the axial width of the channel provided by designing one (75) of the opposing parts of the disks' surfaces related to the channel and confined between the opposing parts of the surfaces of the two adjacent vanes so that it is gradually sloping from the inlet of the channel towards its outlet.

In FIG. 7 the feeding channel is slightly converging from its inlet towards its outlet. The convergence of the feeding channel is provided by designing the boundaries confining the channel between them so that the axial width of the channel decreases gradually from the inlet of the channel towards its outlet, with the gradual decrease in the axial width of the channel provided by designing both (76,77) of the opposing parts of the disks' surfaces related to the channel and confined between the opposing parts of the surfaces of the two adjacent vanes so that they are gradually sloping from the inlet of the channel towards its outlet.

In FIG. 8 the feeding channel is slightly converging from its inlet towards its outlet. The convergence of the feeding channel is provided by designing the boundaries confining the channel between them so that the axial width of the channel and the width between the opposing parts of the surfaces of the two adjacent vanes (79,80) confining the channel between them decrease gradually from the inlet of the channel towards its outlet, with the gradual decrease in the axial width of the channel provided by designing one (78) of the opposing parts of the disks' surfaces related to the channel and confined between the opposing parts of the surfaces of the two adjacent vanes so that it is gradually sloping from the inlet of the channel towards its outlet, and with the gradual decrease in the width between the opposing parts of the surfaces of the two adjacent vanes (79,80) provided by designing the vanes with suitable angles of inclination at their different parts, according to the desired angle of convergence of the channel.

In FIG. 9 the feeding channel is slightly converging from its inlet towards its outlet. The convergence of the feeding channel is provided by designing the boundaries confining the channel between them so that the axial width of the channel and the width between the opposing parts of the surfaces of the two adjacent vanes (83,84) confining the channel between them decrease gradually from the inlet of the channel towards its outlet, with the gradual decrease in the axial width of the channel provided by designing both (81,82) of the opposing parts of the disks' surfaces related to the channel and confined between the opposing parts of the surfaces of the two adjacent vanes (83,84) so that they are gradually sloping from the inlet of the channel towards its outlet, and with the gradual decrease in the width between the opposing parts of the surfaces of the two adjacent vanes provided by designing the vanes with suitable angles of inclination at their different parts, according to the desired angle of convergence of the channel.

In FIG. 10 the feeding channel is slightly converging from its inlet towards its outlet. The convergence of the feeding channel is provided by designing the boundaries confining the channel between them so that the width between the opposing parts of the surfaces of the two adjacent vanes (85,86) confining the channel between them decreases gradually from the inlet of the channel towards its outlet, with the gradual decrease in the width between the opposing parts of the surfaces of the two adjacent vanes (85,86) provided by designing the vanes with suitable angles of inclination at their different parts, according to the desired angle of convergence of the channel.

What is claimed is:

1. A radial out-flowing rotary ram-in compressor comprising:

a stationary casing having at least one inlet passage for admission of working gases, and a receiver wherein pressurized gases collect;

a drive shaft supported for rotation in a given direction inside the casing by an arrangement of bearings; and a rotor assembly comprising a first disk secured for rotation with the drive shaft and lying in a first plane transverse to the rotational axis of the drive shaft; a second disk lying in a second plane transverse to the rotational axis of the drive shaft, with the inner surfaces of the two disks defining an annular space in-between; and a plurality of vanes arranged circumferentially within said annular space, each vane attached to both disks defining the annular space, each vane has a leading edge, a trailing edge, a concave surface and a convex surface, with the average angles of inclination of the successive portions of the vane with respect to a plane comprising the midpoint of the vane and perpendicular to a radial plane including the rotational axis of the rotor and the midpoint of the vane decreases preferably gradually from its leading edge towards its trailing edge, within a range from about +20 to about -10 degrees, the opposing parts of the surfaces of each two adjacent vanes along with the opposing parts of the two disks' surfaces confined between the opposing parts of the surfaces of each two adjacent vanes defining a feeding channel between them, each feeding channel has an inlet communicating with the space relatively radially inward of the vanes and an outlet communicating with the space relatively radially outward of the vanes, the cross sectional area of the inlet of each of the feeding channels being equal to the cross sectional area of its outlet, with means for active sweeping of the pressurized gases from the compressor's receiver being provided.

2. The radial out-flowing rotary ram-in compressor of claim 1, wherein the means provided for active sweeping of the pressurized gases from the compressor's receiver comprises a successive rotary ram-in compressor.

3. The radial out-flowing rotary ram-in compressor of claim 1, wherein the means provided for active sweeping of the pressurized gases from the compressor's receiver comprises a successive rotary ram compressor.

4. A radial out-flowing rotary ram-in compressor comprising:

a stationary casing having at least one inlet passage for admission of working gases, and a receiver wherein pressurized gases collect;

a drive shaft supported for rotation in a given direction inside the casing by an arrangement of bearings; and a rotor assembly comprising a first disk secured for rotation with the drive shaft and lying in a first plane

transverse to the rotational axis of the drive shaft; a second disk lying in a second plane transverse to the rotational axis of the drive shaft, with the inner surfaces of the two disks defining an annular space in-between; and a plurality of vanes arranged circumferentially within said annular space, each vane attached to both disks defining the annular space, each vane has a leading edge, a trailing edge, a concave surface and a convex surface, with the average angles of inclination of the successive portions of the vane with respect to a plane comprising the midpoint of the vane and perpendicular to a radial plane including the rotational axis of the rotor and the midpoint of the vane decreases preferably gradually from its leading edge towards its trailing edge, within a range from about +20 to about -10 degrees, the opposing parts of the surfaces of each two adjacent vanes along with the opposing parts of the two disks' surfaces confined between the opposing parts of the surfaces of each two adjacent vanes defin-

5

10

15

ing a feeding channel between them, each feeding channel has an inlet communicating with the space relatively radially inward of the vanes and an outlet communicating with the space relatively radially outward of the vanes, each of the feeding channels converges from its inlet towards its outlet, with means for active sweeping of the pressurized gases from the compressor's receiver being provided.

5. The radial out-flowing rotary ram-in compressor of claim 4, wherein the means provided for active sweeping of the pressurized gases from the compressor's receiver comprises a successive rotary ram-in compressor.

6. The radial out-flowing rotary ram-in compressor of claim 4, wherein the means provided for active sweeping of the pressurized gases from the compressor's receiver comprises a successive rotary ram compressor.
